UNITED STATES PATENT OFFICE.

MAX CYRIL MORRIS, OF CASTLEBELLINGHAM, IRELAND.

CARBURETOR.

Application filed October 10, 1923, Serial No. 667,602, and in Great Britain October 21, 1922.

The present invention relates to carburetors for internal combustion engines, and more especially to such as are intended for use in connection with motor road vehicles.

5 The principal object of the invention is to provide a carburetor which is of simple and robust construction, which does not involve any complicated or delicate elements giving rise to difficulties or expense in manufacture, or which are easily damaged or put out of adjustment in use, and which offers a very complete atomization of the liquid fuel and also all the chief qualities desirable in a carburetor for road vehicle 10 work including the provision of a substantially uniform proportion of fuel and air as the throttle valve is progressively opened. A further object is to attain the desired uniformity of mixture proportions without 15 calling for any manual operation during running beyond that of opening or closing the throttle valve, and yet another object is to provide a carburetor of this nature which embodies simple means providing for semi- 20 permanent adjustment of the carburetor for different fuels or for engines of different sizes, or for different engine or atmospheric conditions.

With these objects in view, a preferred 25 construction of the carburetor comprises a casing, a main passage therethrough, successive portions of this passage constituting respectively a main air inlet, a mixing chamber and a mixture outlet, a throttle valve 30 consisting of a plunger reciprocable across the said passage, a fuel nozzle located in a well-shaped chamber in the casing opposite to the inner end of the plunger throttle valve, and a tubular member attached to 35 the throttle valve and fitting loosely over the fuel nozzle and within the well-shaped chamber. Such preferred construction embraces also, according to one feature of the present invention, the feature that the tubular member which is a loose fit in the well-shaped chamber and upon the fuel nozzle, is provided on the engine side with a wide longitudinally disposed opening which is progressively exposed to the mixture outlet 40 side of the main passage as the throttle valve is opened. Moreover, according to another feature of the invention, a supplementary air supply is also provided by means of a conduit affording communication 45 solely between the said well-shaped chamber and the exterior of the carburetor and un-

der the control of a manually operated valve or a valve automatically operated by the suction of the engine, or both.

The accompanying drawings illustrate a 60 construction of carburetor in accordance with the present invention and the said invention will now be described more in detail by the aid of reference to these drawings in which:—

Figure 1 is a vertical section taken at right angles to the axis of the mixing chamber and through the axis of the jet, the float chamber which forms no part of the present invention being indicated in dotted lines. 70

Figure 2 is a vertical section on the line 2—2 of Figure 1.

Figure 3 is a fragmentary vertical section on the line 3—3 of Figure 2.

Figures 4 and 5 are respectively a front 75 view and a side view of the plunger valve and tubular member detached from the carburetor.

Referring now to these drawings, 1 is the main casting of the carburetor, the float 80 chamber 2 being indicated in dotted lines. 3 is the inlet for the air and 4 the outlet for the mixture. 5 is the fuel nozzle located in a vertical well 6 in the main casting. For mounting it in position it is provided with an enlarged lower end 7 which is maintained 85 against the shoulder 8 by a short backing plug 9 which is screwed into the internally threaded bore 10 in the casing and is provided with a central orifice 11 for passage of the fuel to the nozzle. 13 is a screwed 90 plug serving to close the bore 10 after the fuel nozzle has been mounted in position and 14 is another screwed plug giving access to the fuel passage 12 for cleaning etc. 95

15 is the main air valve constituted by a piston adapted to be reciprocated transversely to the mixing chamber in the vertical bore 16 by any suitable actuating mechanism. The lower end of this piston valve is preferably cut away obliquely so as to present an inclined face 17 on the air side. The piston carries a downwardly extending tubular member 18 which fits loosely in the annular space between the fuel nozzle 5 and the bore 100 16. This tubular member is shown in part section in Figure 1 and in side elevation in Figure 2 and also, separately in elevation in Figures 4 and 5. 19 is a wide longitudinally disposed opening on the engine side 105 of the tubular member this being formed by cutting away the lower part of this member

on that side, leaving a strip or bar 20 for guiding and strengthening purposes. 21 is a circumferential groove around the piston valve for reducing the suction on the jet 5 hereinafter more fully referred to, and alternative arrangements of providing a small orifice or small orifices on the air side of the tubular member or a bore from the outer end of the piston valve to the interior 10 of the tubular member are indicated in dotted lines at 22 and 23 respectively on Figures 4 and 5. Figures 2 and 3 illustrate another arrangement for the same purpose which is effective throughout the greater 15 range of throttle opening and which embodies an automatic control valve. This arrangement comprises a ball 24 located in a vertical bore 25 and normally resting on a transverse pin 26. The bore 25 is in communication with the outer air through the open lower end 27 thereof and also through one or more side openings 28, and it is also in communication through an orifice 34 with a transverse bore 29 which is in communication with the jet chamber 6. The bore 29 20 is also in communication through an orifice 30 with another bore 31 which is internally screw-threaded to receive a screwed plug 32. By this means the orifice 30 may be partially or wholly occluded by screwing the 25 plug inwards in the bore 31.

The construction of the tubular member, as hereinbefore described, tends to give very 30 complete atomization of the fuel for the following reason. At all openings of the throttle valve (beyond the very first small extent of opening movement while the solid part of the tubular member 18 adjacent to the plunger is within the mouth of the well-shaped 35 chamber 6) the fuel issuing from the orifice at the top end of the nozzle 5 is shielded on the air entry side from the entering main air stream, with the result that the solid jet of fuel is not at first deflected 40 but travels upwards and impinges against the roof and side walls of the tube, so as to receive a preliminary breaking up action, after which it is thrown downwards and 45 forwards through the opening 19 in the member, and is then caught up in the main air stream, which is in a whirling condition, owing to its having been deflected under the bottom of the plunger, and from the 50 surfaces of the tubular member and the side walls of the main passage. The main opening 19 is of quite substantial width relative 55 to the area available for fuel outlet from the nozzle and said opening is intended to permit of the suction in the mixing chamber in the region of the mouth of the well-shaped chamber being fully effective on the fuel outlet orifice. Said opening 19 is in 60 no sense a measuring opening or valve for controlling the amount of liquid fuel delivered into the main air stream. Thus the 65

opening 19 shown may be considered (apart from the strip or bar 20 left for guiding or strengthening purposes) as being formed by slicing away about half of the cylindrical body of the tube to leave a tongue on the air entry side which functions only or principally to shield the fuel stream from the entering air.

It will be observed that by the employment of the "straight-through" type of carburetor with a plunger valve moving across the main passage and in the region of the fuel nozzle, a very simple and inexpensive construction is provided. This type of carburetor, however, has the well-known disadvantage that at small throttle openings when the speed of air passing beneath the plunger is very high relatively to the total volume of air passing in other words, when there is a strangling action on the air, there 85 is an unduly high proportionate degree of suction upon the fuel, this degree progressively lessening as the plunger valve is opened and it will be noted that the present invention as hereinbefore described provides for correction of this disadvantage by lessening the proportionate degree of suction at small throttle openings by permitting inleak of air from the exterior of the carburetor into the well-shaped chamber 6. 95

For purposes of description, it will be convenient to consider separately the two methods of admitting outside air into the well-shaped chamber which are illustrated in the drawings, namely the method which includes provision of the screw plug valve 32 and the method which includes provision of the automatic ball valve 24. Considering first the latter, and disregarding the valve 32 and air inleak orifice 30, with small 100 throttle opening and slow running of the engine, the ball 24 will be retained by gravity in the position shown in full lines so that outside air can enter freely through the orifices 28 and 34 and the bore 29 into the well-shaped chamber from whence it passes upwards and debouches into the main air stream at the mouth of the well-shaped chamber in the immediate region or in advance of the fuel outlet orifice. The degree 105 of suction due to the engine which in the absence of the controlling air admitted would be effective on the fuel, is reduced owing to the admission of the controlling air into the main air stream in the immediate vicinity of the fuel orifice. On account of the fact that the strangling action of the throttle on the main air stream is reduced the suction at the mouth of the well-shaped chamber increases, although the ratio of this suction to the total 110 volume of air passing decreases with opening of the throttle. When a certain degree of suction is attained, the ball valve 24 is drawn up into the position shown in dotted lines in Figure 2, thus closing the orifice 34 115 120

130

and thus cutting off communication between the well-shaped chamber and the outer air. This valve thus acts to reduce the proportionate degree of suction upon the fuel during a certain extent of opening movement of the throttle and beyond this extent of opening removes the correction thus provided, that is to say, when it is no longer necessary or of such degree of importance.

10 Considering now the method of admitting air which embraces the screw plug valve 32, and disregarding the opening 34 controlled by the ball valve, outside air is admitted through the end 33 of the screwed bore 31, that part of opening 30 which is uncovered by the plug 32, and bore 29 to the well. The amount of air admitted is thus dependent upon the position of the plug 32 in relation to the orifice 30, which position may be 15 varied at will. The effect of the entering air is as before to reduce the proportionate degree of suction upon the fuel and in this case the correction applied is effective throughout the whole range of throttle opening. It is to be noted, however, that the 20 correcting effect will be proportionately reduced as the throttle valve is opened and the total volume of air passing becomes progressively greater compared with the maximum amount 25 of air which can pass through the restricted opening 30.

It is preferred, however, to employ the two methods just described in combination in one structure as illustrated in the drawings, and in a carburetor as so constructed the main correction is effected by the ball valve arrangement, the other arrangement of the plug 32 serving as a fine adjustment which can be set to determine the point at 30 which the ball valve operates, and moreover serving as a means for semi-permanent adjustment of the carburetor for different fuels or for engines of different sizes or for different engine or atmospheric conditions.

40 The object of the groove 21 is to provide a small by-pass for air past the throttle valve to reduce the extremely excessive suction on the fuel orifice during the very first movement of opening of the throttle valve, and it will be noted that as soon as the valve has been very slightly raised the groove 21 becomes enclosed within the bore 16 and is no longer effective as a by-pass for air. In this connection it is to be noted that, the tubular member 18 being a designedly loose fit within the well-shaped chamber 6, the suction is available at the jet, and fuel is actually drawn up through the annular space between the said tubular member and the wall 45 of the well-shaped chamber even at very small opening of the throttle valve before the solid portion of the tube is withdrawn from the mouth of the said member. Parts 50 22 and passages 23 are shown in dotted lines in Figures 4 and 5 merely for the purpose

of showing how additional air supplies may or may not be provided. One of these alternatives embraces a small diameter passage 23 bored from the upper end of the throttle valve into the interior of the tubular member, and another alternative embraces a small orifice 22 formed in the tubular member on the air entry side. No means for rendering such passage or orifice positively ineffective are described but it will be readily understood that for practical purposes they become rapidly ineffective as the throttle valve is raised.

Moreover, as shown in the drawings it is preferred to leave the tube 18 solid for a short distance below the throttle valve, this portion blocking the mouth of the well at extremely small throttle openings and so strangling to some extent the suction on the fuel at such openings.

85 As previously stated however, the tubular member 18, is a loose fit both over the fuel nozzle 5, and within the well 6 so that at the extremely small throttle opening just referred to the effect of the complete portion 90 of the tubular member above the opening 19 is only to strangle and not entirely to cut off the passage of fuel.

95 What I claim and desire to secure by Letters Patent of the United States is:—

1. In a carburetor, the combination of a plunger valve movable diametrically across the main passage, said plunger valve having a circumferential groove thereon adapted to permit an inleak of air through the main passage past the said valve when the latter is in the closed position and during a small degree of opening movement thereof, and to be enclosed by the casing on continued opening movement of the said valve, a tubular member carried by the plunger valve, a well-shaped chamber formed in the casing opposite to the said valve, and a fuel nozzle disposed axially in the said well-shaped chamber, the said tubular member being adapted to reciprocate synchronously with movement of the said plunger valve loosely within the annular space between the wall of the well-shaped chamber and the fuel nozzle and being provided on the engine side thereof with a wide longitudinally disposed opening which is progressively exposed to the main passage on the engine side as the throttle valve is progressively opened.

110 2. In a carburetor having a plunger throttle valve movable diametrically across the main passage, the combination of a tubular member carried by the plunger valve, a well-shaped chamber formed in the casing, opposite to the said valve, a fuel nozzle disposed axially in the said well-shaped chamber, the said tubular member being adapted to reciprocate, synchronously with movement of the said plunger valve loosely within the annular space between the wall of the well- 115 120 125 130

- shaped chamber and the fuel nozzle and being provided on the engine side thereof with a wide longitudinally disposed opening which is progressively exposed to the main 25 passage on the engine side as the throttle valve is progressively opened, a conduit affording communication solely between the said well-shaped chamber and the exterior of the carburetor, and an automatic valve 30 10 adapted normally to occupy a position giving free access of air through said conduit and to be actuated by suction to obstruct the passage of air through said conduit on a predetermined degree of suction being attained 35 15 at the mouth of the said well-shaped member.
3. In a carburetor having a plunger throttle valve movable diametrically across the main passage thereof, the combination 40 20 of a well-shaped chamber formed in the casting opposite said valve; a fuel nozzle disposed axially of said well-shaped chamber, a tubular member carried by said plunger valve, said tubular member being adapted to 45
- reciprocate synchronously with the movement of said plunger valve loosely within the annular space between the wall of the well-shaped chamber and the fuel nozzle and being provided on the engine side thereof with a wide longitudinally disposed opening 30 which is progressively exposed to the main passage on the engine side as the throttle valve is progressively opened; conduit means affording communication solely between said well-shaped chamber and the exterior of the carburetor; two openings communicating to the exterior of the carburetor therein; manually operable means for adjusting the effective area of one of said openings; and an automatic valve adapted normally to freely admit air through the other of said openings and to be actuated by suction to obstruct the last mentioned opening on a predetermined degree of suction being attained in the main passage at the mouth of the well-shaped chamber. 45

MAX CYRIL MORRIS.
